[57] CLAIM

The ornamental design for a voltage converter or the like, substantially as shown and described.

DESCRIPTION

FIG. 1 is a front elevational view of a voltage converter or the like incorporating my new design.

FIG. 2 is a left side view of the voltage converter of FIG. 1. The right side view is the mirror image thereof. FIG. 3 is a rear elevational view of the voltage converter of FIG. 1.

FIG. 4 is a top plan view of the voltage converter of FIG. 1.

FIG. 5 is a bottom plan view of the voltage converter of FIG. 1.
